UNITED STATES PATENT OFFICE.

JOHN RITCHIE RICHMOND, OF GLASGOW, SCOTLAND.

STEAM SURFACE CONDENSER.

SPECIFICATION forming part of Letters Patent No. 716,760, dated December 23, 1902.

Application filed August 4, 1902. Serial No. 118,354. (No model.)

To all whom it may concern:

Be it known that I, JOHN RITCHIE RICHMOND, a subject of His Majesty the King of Great Britain, residing at Glasgow, Scotland, 5 have invented a certain new and useful Improvement in Steam Surface Condensers, of which the following is a specification.

My invention relates to steam surface condensers of that class in which the circulating water passes through the tubes and the steam is on the outside of the latter.

The object of my invention is to provide a simple and effective construction of apparatus in which the air and water of condensation 15 can be withdrawn separately, the latter particularly being taken off before it is unduly cooled and its heat wasted.

A construction of apparatus according to my invention is illustrated in the accompanying drawings, in which—

Figure 1 is a longitudinal section. Fig. 2 is a plan. Fig. 3 is a section on line A A, Fig. 1, looking in direction of the arrow. Fig. 4 is a section in line B B, Fig. 1, looking 25 in the direction of the arrow. Fig. 5 is a section on line C C, Fig. 1, looking in the direction of the arrow.

The condenser consists of a casing *a*, having tube-plates *b b* at either end, between 30 which are supported the tubes *c* for the circulating water. The inclosing ends *d d* of this casing *a* thus form two chambers *e e*, the latter being divided longitudinally by a diaphragm *g*, Fig. 4. With the chambers so 35 formed on either side of diaphragm *g* are connected an inlet *h* and outlet *i*, respectively, for the circulating water.

The portion of the condenser between the tube-plates *b b* forms a chamber, which is divided 40 into two portions by a transverse division plate or diaphragm *j*, having an aperture *k*, Fig. 5, on the opposite side to the steam-inlet, hereinafter referred to, such plate *j* being so situated that the larger or primary 45 portion of the condenser on the right is two-thirds (or more) and the smaller or secondary portion on the left is one-third (or less) of the whole. In the larger or primary portion may be arranged, as shown, a steady-plate *l*, Fig. 50 3, for the tubes, such plate having apertures *m n o* or being otherwise more or less open for the circulation of steam in the larger por-

tion. To enable this to be effectual, some of the tubes are omitted, as shown, where these gaps occur, one of them, *o*, corresponding 55 with the gap *k* in the division-plate *j*. The plate *l*, however, is, as stated, merely a steady-plate and is not intended to fulfil the purpose of a diaphragm. Connected with the larger or primary chamber is a steam-inlet *p* in such 60 a manner that the steam enters at right angles to the tubes *c*, and with the smaller or secondary chamber is connected an air-outlet *q*, while the two chambers in addition to being connected by the gap *k* are connected 65 by a siphon-pipe *r*. The larger or primary chamber is provided with a float-tank *s* of the usual kind.

In operation the cooling-water enters inlet *h* and circulates through one half of the tubes, 70 then through chamber *e*, and returns by the other half to outlet *i*. The steam enters through inlet *p* and mainly condenses in the larger or primary portion of the condenser, though a portion will pass into the smaller or 75 secondary portion, the water of condensation in the latter chamber passing by siphon-pipe *r* into the larger, where it joins the water of condensation of the latter and passes to the float-tank and away. 80

The air, it will be seen, can be withdrawn by a pump or in other ways from the outlet *q* in the smaller chamber at a comparatively low temperature, while the bulk of the water of condensation from the larger chamber remains at a comparatively high temperature 85 and can be withdrawn in that condition.

The construction enables a considerable efficiency in working to be secured.

What I claim is—

1. In a steam surface condenser and in combination, a chamber having a primary portion and a secondary portion, the former being of considerably greater size than the latter, and having an outlet for the water of condensation while the latter has an outlet for the air, a diaphragm forming a division between such chambers, and having an opening therein, means connecting the two chambers for drawing the water of condensation from the secondary to the primary and means for circulating cooling-water through such chambers, substantially as described. 95
2. In a steam surface condenser, and in com- 100

bination a chamber *a*, circulating-water tubes *c* therein means for supporting same and chambers *e*, *f*, having inlet and outlet for the circulating water a partition-plate *g* dividing 5 the chamber *f* between the inlet and outlet, a diaphragm *j* dividing the chamber *a* into a primary and secondary portion of which the primary is the larger said primary portion having an opening forming a steam-inlet and 10 an opening forming an outlet for the water of condensation and said secondary portion

having an opening forming an air-outlet, and a siphon-pipe connecting the primary and secondary chambers substantially as described.

In testimony whereof I have hereunto set my hand in the presence of two subscribing witnesses.

JOHN RITCHIE RICHMOND.
